UNITED STATES PATENT OFFICE.

DESIGN FOR A CARPET-BORDER.

SPECIFICATION forming part of Design No. 23,822, dated November 27, 1894.

Original application filed August 22, 1894, Serial No. 521,035. Divided and this application filed October 12, 1894. Serial No. 525,731. Term of patent 3½ years.

To all whom it may concern:

Be it known that I, ARTHUR MIDDLETON ROSE, residing at Yonkers, county of Westchester, State of New York, have invented and produced a new and original Design for a Pattern to be Wrought in Brussels and Wilton Carpet Borders in such Colors as May be Desired, of which the following is a specification.

This application is a division of application, Serial No. 521,035, filed by me August 22, 1894, wherein the border is claimed in combination with a suitable body therein shown.

The design of the border consists of a narrow edge intended to lie right along the line of the carpet breadth, then a broad band of

lace work character bounded by a series of reversed arches, then an outer edge or heel having ornamental figures at the ends and bows of these arches, with a line of bead work lying outside of these latter figures.

What I claim, and desire to secure by Letters Patent, is—

The design for a carpet border, substantially as shown.

Signed by me in New York city, this 5th day of October, 1894. 25

ARTHUR MIDDLETON ROSE.
